(57) **CLAIM**

The ornamental design of an airway cup assembly, as shown and described.

DESCRIPTION

FIG. 1 is an isometric view of an embodiment of an airway cup assembly illustrating the new design;
FIG. 2 is a front view thereof;

FIG. 3 is a rear view thereof;

FIG. 4 is a right-side view thereof;

FIG. 5 is a left-side view thereof;

FIG. 6 is a top-view thereof;

FIG. 7 is a bottom-view thereof;

FIG. 8 is an isometric view of the airway cup assembly of FIG. 1, but shown in an open configuration;

FIG. 9 is a front view of FIG. 8;

FIG. 10 is a rear view of FIG. 8;

FIG. 11 is a right-side view of FIG. 8;

FIG. 12 is a left-side view of FIG. 8;

FIG. 13 is a top-view of FIG. 8; and,

FIG. 14 is a bottom-view of FIG. 8.
